CLAIM

The ornamental design for a video processor for a still video camera, as shown and described.

DESCRIPTION

FIG. 1 is a front, top and right side perspective view of a video processor for a still video camera, showing our new design;

FIG. 2 is a rear, bottom and left side perspective view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a right side elevational view thereof;

FIG. 8 is a left side elevational view thereof; and

FIG. 9 is a top, front and right side perspective view thereof.

The broken line showing of the still video camera and the television set in FIG. 9 is for illustrative purposes only and forms no part of the claimed design.
